UNITED STATES PATENT OFFICE.

FRANK V. CARMAN, OF OAKLAND, CALIFORNIA.

RAILWAY-TIE-ADZING MACHINE.

1,427,516.

Specification of Letters Patent. Patented Aug. 29, 1922.

Application filed December 27, 1921. Serial No. 524,951.

To all whom it may concern:

Be it known that I, FRANK V. CARMAN, a citizen of the United States, residing at Oakland, in the county of Alameda and State of California, have invented certain new and useful improvements in Railway-Tie-Adzing Machines, of which the following is a specification.

My invention relates to a machine for 10 hewing or cutting down the upper surfaces of railway cross-ties.

In railway track maintenance, it is necessary, from time to time, to replace the tie plates upon which the rails rest, and when 15 so doing, it is customary to hew or cut down the upper surfaces of the ties, in the regions of the tie plates, in order to provide new and sound seats for the new plates. This is especially necessary when the new plates are 20 heavier or thicker than those replaced, so that the rail, when re-laid, will have the same height as it formerly had. The object of my invention, therefore, is to provide a machine for thus cutting or adzing the ties 25 quickly, accurately, and economically, thereby eliminating considerable hand labor, and saving time. The time-saving feature of my invention is of particular importance, affecting as it does the length of time that the 30 track is out of commission and the consequent delay of traffic.

Broadly speaking, my invention comprises a movable truck or carriage, upon which is mounted a cutter and power means for operating the same. One rail of the track is left in place, and the carriage is guided and partly supported thereby. Further support is had directly from the ties. As the carriage is moved along the track, manually or 40 otherwise, its cutter, in passing over the successive ties, hews therein a shallow kerf of suitable width to receive the tie plates. It is to be understood, however, that although my invention is herein described and illustrated in its preferred form, changes within 45 the scope of the claims hereto appended, may be made in the form and construction of the machine, without affecting in any way the essentials of the invention or departing from 50 the spirit thereof.

With this in view, my invention will now be fully described with reference to the accompanying drawings, wherein:—

Fig. 1 is a plan view of my complete tie-adzing machine.

Figs. 2^a and 2^b are longitudinal sections of

a tie, enlarged, showing respectively a horizontal and an inclined kerf as cut by my machine.

Fig. 3 is a side elevation of my machine. 60

Fig. 4 is an end elevation thereof.

Figs. 5 and 6 are detailed elevations, enlarged, of one of the supporting rollers, viewed respectively from the side and end of the machine. 65

Fig. 7 is a detailed elevation of one of the guiding and supporting wheels as viewed from the end of the machine.

Fig. 8 is a detailed elevation, enlarged, of the cutter shaft, as viewed from the side of 70 the machine.

Fig. 9 is a part sectional elevation of the same, as viewed from the end of the machine, taken on the line 9—9 of Fig. 8.

Figs. 10 and 11 are detailed sectional plan 75 views taken respectively on the lines 10—10 and 11—11 of Fig. 8.

Fig. 12 is a plan view of the cutter head, taken on the line 12—12 of Fig. 8.

In the drawings, and referring particularly to Figs. 1 and 4 thereof, the reference numeral 1 designates the rail which is left in place, and 2 the ties which are to be adzed for the reception of the tie plates of the other rail. This second rail and said tie 85 plates have been removed, and therefore do not appear in the drawings.

My machine comprises a truck or carriage frame 3, which is supported at one side by flanged wheels 4 adapted to run on the rail 90 1. Said wheels, as shown in Figs. 1, 4 and 7, are flanged upon both sides, the inner flange 5 being greater in diameter than the outer flange 6, so that when crossing frogs, although said outer flange will ride up and 95 lift the wheel off the rail 1, the inner flange 5 will still project below the top of said rail and serve as a guide. The other side of the frame 3 carries a longitudinally disposed up-turned channel member 7, Figs. 1, 3, 4, 100 5 and 6, beneath which are mounted a series of supporting rollers or wheels 8 adapted to run upon the surfaces of the ties 2. There are a sufficient number of such wheels or rollers 8 to insure adequate bearing support 105 for that side of the carriage.

The frame 3 carries a platform 9, Figs. 1, 3 and 4, upon which is mounted an engine 10. A pulley 11 upon the shaft of said engine is connected by a belt 12 with a pulley 13 fixed 110 upon a vertical shaft 14. Said shaft is partly supported in a suitable channel-section

bracket 15, and carries at its lower end a cutter head 16. This cutter head may be of any form or construction suitable for hewing a kerf in the ties 2, but in its preferred form as shown in Figs. 8, 9 and 12 of the drawings, comprises a spider having arms 17 to which are secured adjustable and removable blades 18, said blades being sharpened for cutting upon their lower and outer edges, as shown at 19. As the entire machine is moved along the track, by hand or otherwise, the continuously revolving cutter head 16 hews a shallow groove across each succeeding tie 2, as shown in section at 20 in Fig. 2^a. The depth of said groove is regulated by mechanism to be described presently. Moreover, the bottom of said groove may, if desired, be inclined slightly, as shown in Fig. 2^b, to give the rail 20 a slight inward slant.

The upper portion of the cutter shaft 14 is supported by a bearing block 21, Figs. 8, 9 and 11, mounted in the channel bracket member 15 and adapted for a limited transverse 25 sliding movement therein. Bolts 22, upon which said block 21 is freely slideable, serve to retain it in position, and a removable bar 23 is provided to hold said block at either end of its play. Thus by removing 30 said bar 23 from the position shown in full lines in Figs. 9 and 11, the bearing block 21 may be shifted laterally, and said bar replaced at the other side, as shown by the dotted lines. This shifts the upper end of 35 the shaft 14, causing it to assume an inclined position, and thereby causing the cutter 16 to make the inclined slot shown in Fig. 2^b.

The lower portion of said shaft 14 is carried in a bearing block 24, Figs. 8 and 9, seated within the channel member 7, and adapted for rocking movement therein, as shown. Above said block 24, and separated therefrom by a thrust bearing 25, is a collar 26 which is compelled to rotate with the 45 shaft 14 by keys 27, but within which said shaft is free to slide longitudinally. A second collar 28 is spaced above the collar 26, and is adjustably secured to said shaft by a nut 29. A compression spring 30 interposed between the collars 26 and 28, normally holds the shaft 14 at the upper limit of its vertical movement, in which position the cutter head 16 is raised above the surfaces of the ties and is therefore inoperative.

55 The extreme upper end of the shaft 14 has a thrust bearing within a block 31, Figs. 8 and 9, carried by a screw 32 which is threaded through a nut 33 and is provided at its upper end with a crank or handle 34. 60 The nut 33 is slidably mounted in guides 35, Figs. 8, 9 and 10, which permit it to move laterally to follow the shaft 14 when the latter is shifted away from its true vertical position as described above. Screwing down 65 the thrust block 31 by means of the handle

34 thus lowers the shaft 14, against the action of the spring 30, to bring the cutter head 16 into operative position, and also to regulate the depth of the cut. Moreover, if it be desired to skip one or more ties entirely, the cutter 16 can be raised, out of its operative position, by means of said handle 34, without stopping or otherwise interfering with the operation of the machine. In order to prevent slipping of the belt 12 when the upper end of the cutter shaft 14 is shifted inwardly, there may be provided a tightener for said belt of any suitable form, indicated at 36 in Fig. 1 of the drawings.

I claim:—

1. A railway-tie adzing machine comprising a carriage adapted to be moved along a railway track; a substantially vertically disposed rotatable shaft, carrying at its lower end a cutter head adapted to hew across the ties as the carriage advances; a laterally rocking, rotary bearing for supporting the lower portion of the shaft on the carriage, and in which the shaft is vertically movable, said bearing consisting of a rocking block mounted on the carriage and a collar fixed upon the shaft above and rotatably supported on the block; a second collar adjustably mounted on the shaft above the first collar; a spring between said collars to normally hold the shaft up and lift its cutter head above the ties; and a vertically and laterally adjustable thrust bearing associated with the top of the shaft, to vertically adjust and to tilt the shaft and cutter head. 100

2. A railway-tie adzing machine comprising a carriage adapted to be moved along a railway track; a substantially vertically disposed rotatable shaft, carrying at its lower end a cutter head adapted to hew across the ties as the carriage advances; a laterally rocking, rotary bearing for supporting the lower portion of the shaft on the carriage, and in which the shaft is vertically movable; a spring associated with said bearing and shaft to normally hold the shaft up and lift its cutter head above the ties; and a vertically and laterally adjustable thrust bearing associated with the top of the shaft, to vertically adjust and to tilt the shaft and cutter head, consisting of a laterally slideable nut mounted on the carriage, a block bearing on the shaft; and a screw threaded through the nut and operating on the block. 110

3. A railway-tie adzing machine comprising a carriage adapted to be moved along a railway track; a substantially vertically disposed rotatable shaft, carrying at its lower end a cutter head adapted to hew across the ties as the carriage advances; a laterally rocking, rotary bearing for supporting the lower portion of the shaft on the carriage, and in which the shaft is vertically movable, said bearing consisting of a rocking block mounted on the carriage 130

and a collar fixed upon the shaft above and rotatably supported on the block; a second collar adjustably mounted on the shaft above the first collar; a spring between the two collars to normally hold the shaft up and lift its cutter head above the ties; and a vertically and laterally adjustable thrust bearing associated with the top of the shaft, to vertically adjust and to tilt the

shaft and cutter head, consisting of a laterally slideable nut mounted on the carriage; a block bearing on the shaft; and a screw threaded through the nut and operating on the block.

In testimony whereof I have signed my name to this specification.

FRANK V. CARMAN.
